Patented July 20, 1920.

Frederick J. Troll. Inventor
By *Edward Hammel* Attorney

UNITED STATES PATENT OFFICE.

FREDERICK J. TROLL, OF BALTIMORE COUNTY, MARYLAND, ASSIGNOR TO THE LOADOMETER COMPANY, OF BALTIMORE, MARYLAND, A CORPORATION OF DELAWARE.

DESIGN FOR A LOAD-MEASURING DEVICE.

55,901.

Specification for Design.

Patented July 20, 1920.

Application filed April 20, 1920. Serial No. 375,401. Term of patent 3½ years.

To all whom it may concern:

Be it known that I, FREDERICK J. TROLL, a citizen of the United States of America, and resident of Baltimore county, State of Maryland, have invented a certain new, original, and ornamental Design for a Load-Measuring Device, of which the following is a specification.

In the accompanying drawing I have illustrated a load measuring device constructed in accordance with my invention.

The figure is a side elevation of the same.

The device consists of a fluid pressure cylinder, 1, the cylinder having grips or handles, 2, and a piston rod, 3. Seated in the piston rod, 3, is an upright screw, 4, carry-

ing a load-engaging member, 5, and there is a hand lever, 6, for turning the screw. Mounted on the cylinder as shown is a pressure gage, 7, for indicating the load.

What I claim and desire to secure by Letters Patent is:

The ornamental design for a load measuring device, substantially as shown and described.

Signed by me at Baltimore, Maryland, this 19th day of April, 1920.

FREDERICK J. TROLL.
